UNITED STATES PATENT OFFICE.

HERMAN C. PRIEBE, OF CHICAGO, ILLINOIS.

TANK-CAR UNDERFRAME.

1,111,491.

Specification of Letters Patent. Patented Sept. 22, 1914.

Application filed January 14, 1910. Serial No. 537,981.

To all whom it may concern:

Be it known that I, HERMAN C. PRIEBE, a citizen of the United States, residing in Chicago, in the county of Cook and State of Illinois, have invented a new and useful Improvement in Tank-Car Underframes, of which the following is a specification.

My invention has for an object the providing of a tank-car with an underframe construction wherein the tank is supported upon the center-sills with maximum security and simplicity of attachment, and in such manner that end-thrust of the tank is directly sustained by the center-sills; and the invention has for further objects such other improvements in structure or function as may be found to obtain in the devices hereinafter described or claimed.

In the accompanying drawings, forming a part of this specification, and in which like reference numerals indicate like parts in all of the figures, Figure 1 is a longitudinal sectional view of one of the duplicate ends of a tank-car underframe embodying the construction of my invention, with the upper part of the car-tank broken away; Fig. 2 is a section on the line 2—2 of Fig. 1; Fig. 3 is a section on the line 3—3 of Fig. 1.

10—10 are the channel iron center-sills of the underframe. 11 is the body bolster secured to said sills.

12 is the tank; and at each end of this tank there is rigidly secured to its bottom the cradle-casting 13, positioned near the body bolster and on the side thereof away from the adjacent end of the car. The top member 14 of this cradle-casting is elongated and shaped to conform with the curvature of the portion of the tank bottom to which it is riveted; and the shoulders 15 rest upon the top of the upper flanges of the channel iron center-sills, thus directly supporting said cradle-casting upon said center-sills. The downward projection 16 of said cradle-casting is fitted down within and between the opposed inner faces of the vertical webs of the center-sills, the said casting being thus socketed to said sills and holding the tank from lateral movement in reference to the sills. The said downward projection of the cradle-casting is provided with a transverse keyway 17, which registers with corresponding keyways 18 in the respectively opposed vertical webs of the sills. A horizontal flattened key 19 is passed through these mutually registering key-

ways, and is retained in position by the cotter-pins inserted in its projecting opposite ends. This keying of the cradle-casting to the center-sills provides an extremely simple and effective securing of the tank to the sills; and all end-thrust of the tank, resulting from buffing shocks or other cause, is directly sustained by the sills, being immediately transmitted thereto through the cradle-castings and the key whereby said castings engage the sills.

By reason of the fact that the sills thus sustain all end-thrust of the tank, through the cradle-castings thus resting upon and secured to them between the body bolsters, the tank head-block 20 is relieved of all end-thrust of the tank and may be dispensed with entirely, except in so far as such head-block is retained as a mere protection to the bottom of the rim of the tank-end. Dispensing with the head-block is in many instances deemed desirable and of substantial advantage in the construction of the car. But when the head-block is present, it may conveniently be held in place by the L-shaped head-block tie-plate 21, whose horizontal member passes under the head-block and is secured to the top flanges of the sills, and whose vertical member projects upward against the outside face of and above the head-block, the head-block thus being seated in the angle of said tie-plate. And then the end 22 of the tank is conveniently and effectively secured to the said head-block tie-plate by means of the tank-end tie-plate 23 whose upper end is riveted to the center of the tank-end and whose lower end is detachably bolted, at 24, to the top of the vertical member of the head-block tie-plate, thus providing an especially convenient and effective means of securing the tank to the sills at each of the extreme ends of the car. To sustain any tendency to lateral swaying of the tank, in reference to the underframe, there are also provided, over each body-bolster, a pair of heel-castings 25, secured to the lower portion of the side of the tank-bottom over the respectively opposite lateral members of the body bolster, the flat bottom of each such heel-casting being adopted to make contact with the top face of the corresponding lateral member of the body-bolster, in the manner indicated in Fig. 2. These lateral heels serve to relieve the cradle-castings, and the tank-bottom, of some of the strain that would be put upon them by any tendency of

the tank to lateral swaying. The tying of the tank ends to the sills, by the above described tie-plates, also serves to relieve the keys, in the cradle-castings, of some strain 5 that might be put upon them by any shock or stress that would tend to lift the tank at its either end.

The keys connecting the sills with the cradle-members are freely removable or dis- 10 connectible without any such mutilation of parts as would be involved in the removal of rivets; and so also, such keys may be freely put in place, and effect the connec- 15 tion of the sills with the cradle-members, without any such operation as the permanent heading-up of rivets. It will also be observed that the heel-castings bear freely upon, and are free of any connection with, 20 the body-bolsters, thus providing for the lateral support of the tank without preventing the free securing or detaching of the tank by the mere inserting or removal of the aforesaid freely removable keys.

My invention is hereinabove set forth as 25 embodied in one particular form of construction, but I do not limit it thereto or to less than all the possible forms in which the invention as hereinafter claimed may be embodied and distinguished from any prior 30 device for like purpose.

I claim:

1. In a tank-car, in combination: a tank; center sills; a cradle-member rigidly secured to the bottom of the tank and sup- 35 ported upon and socketed to the center-sills; and a transverse freely removable key passed through mutually registering key- ways in said center sills and cradle-members; substantially as specified.
2. In a tank-car, in combination; a tank; center-sills; a cradle-member rigidly se- 40 cured to the bottom of the tank and sup- ported upon and socketed within the center-

sills; and a transverse freely removable key passed through mutually registering key- 45 ways in said center-sills and cradle-members; substantially as specified.

3. In a tank-car, in combination: a tank; center-sills; a cradle-member rigidly se- 50 cured to the bottom of the tank and sup- ported upon and socketed to the center-sills; and a horizontally transverse freely removable key passed through mutually registering key-ways in said center-sills and cradle- member; substantially as specified. 55

4. In a tank-car in combination: a tank; center-sills; a cradle-member rigidly se- 60 cured to the bottom of the tank and sup- ported upon and socketed within the center- sills; and a horizontally transverse freely removable key passed through mutually registering key-ways in said center-sills and cradle-member; substantially as specified.

5. In a tank-car, in combination: a tank; center-sills; body-bolsters; supporting means 65 to secure said tank upon said center-sills; and heel-castings secured upon either side of the lower part of said tank and adapted to bear freely upon the body-bolster, to prevent lateral swaying of the tank; sub- 70 stantially as specified.

6. In a tank-car, in combination: a tank; center-sills; supporting means to sustain 75 said tank upon said center-sills; a head- block at the end of the tank; a tie-plate secured to the sills at the head-block; and a further tie-plate secured to the head of the tank and detachably connected to the afore- said tie-plates; substantially as specified.

In testimony whereof I hereunto set my 80 hand in the presence of two subscribing witnesses.

HERMAN C. PRIEBE.
